GARMENT STRUCTURE

Armigene Roderick Johnson, Wantagh, N. Y.

Application February 14, 1955, Serial No. 487,796

2 Claims. (Cl. 2—106)

This invention relates to garments and more specifically to an improved sleeve for blouses, shirts and other similar wearing apparel that will permit greater freedom of action and will enable the arms to be raised above the head without causing the blouse or shirt body being raised and withdrawn from its normal position beneath a waist belt. At the same time the improved sleeve structure does not produce bunching of the material beneath or in front of the shoulder and provides a neater, more orderly appearing garment. Considerable effort has been devoted to blouse and shirt construction in order to provide a more comfortable garment that will stay in place even when the wearer engages in activities requiring free use of the arms. Gussets beneath the arm and other similar devices have been employed to add greater freedom but while some success may have been attained, the added material has detracted from the appearance of the garment and bunching under the arms is not only noticeable but interferes with the comfort of the wearer.

Accordingly one object of the invention resides in the provision of a blouse or shirt having an improved sleeve structure enabling greater freedom of action without pulling the garment upwardly about the waist of the wearer and at the same time afford an improved appearing sleeve without the bunching of material about the shoulder and upper arm part.

Another object of the invention resides in the provision of an improved sleeve structure wherein the sleeve and body portions of the garment are connected one to the other so that the material forming these garment parts will be properly distributed about the shoulder to provide improved appearance and greater freedom of action.

Still another object of the invention resides in the provision of an improved sleeve structure and method of attachment to a garment that causes the sleeve to drape uniformly over the arm with the basic support being from the upper side of the garment shoulder to relieve the stresses placed on the garment when the arms are raised. This is particularly important in the case of blouses and shirts for both men and women since the garment will not pull from beneath the skirt or trousers and produce an untidy, unkept appearance after the arms have been raised several times.

The above and other objects and advantages of the invention will become more apparent from the following description and accompanying drawings forming part of this application.

In the drawings:

Figs. 1, 2 and 3 are perspective views of a sleeve structure in accordance with the invention showing the freedom afforded to the wearer as the arm is raised and lowered;

Figs. 1A, 2A and 3A illustrate the behavior of a prior art sleeve structure and its effect on the shirt or blouse;

Fig. 4 shows the development of the upper end of a sleeve in solid lines in accordance with the invention

and for comparison purposes the prior art sleeve is shown in dotted outline;

Fig. 5 is a side elevation of a sleeve in accordance with the invention prior to attachment to a shirt or blouse and with the sleeve lying flat;

Fig. 6 corresponds to Fig. 5 and illustrates the prior art sleeve;

Fig. 7 shows the sleeve in accordance with the invention in full line as compared with a prior art sleeve shown in dotted outline;

Fig. 8 illustrates the sleeve of Fig. 5 as attached to a blouse and for the purpose of emphasizing the freedom of action attained by the wearer without disturbing the blouse itself; and

Fig. 9 illustrates a prior art structure showing its reaction on the blouse to even slight movement of the arm of the wearer.

While the invention now to be described is generally applicable to garments of all types for men, women and children of cloth and other similar materials, it is particularly useful in the case of shirts and blouses adapted to be tucked in beneath a waist belt or a skirt, trousers or the like. As previously pointed out conventional shirt and blouse structures do not provide sufficient freedom for the wearer so that the arms can be raised and lowered without causing the garment to pull out from beneath the waist belt and thus look shabby and unkempt. This situation is substantially completely avoided by a sleeve in accordance with the invention which is so arranged and designed as to provide this added freedom without utilizing gussets or other structures involving the provision of additional material beneath the arms and thus detracting from the appearance of the garment.

Referring now to Figs. 1 and 1A the former illustrates a lady's blouse in accordance with the invention and with the arm in a lowered position. The sleeve 10 at its point of attachment 11 to the blouse 12 gives the appearance of a conventional or prior art sleeve such as that shown in Fig. 1A. As will be shown that portion of the sleeve 10 about the upper part of the arm in accordance with the invention is slightly larger in diameter than the conventional sleeve and by reason of its improved attachment to the blouse 12 tends to drape downwardly over the top of the arm forming a more attractive looking garment. Note in both figures that an X has been placed at the waist line in order to illustrate the point of the blouse at the intersection of the waist belt 13.

Fig. 2 shows the arm 10 in the raised position. Note that the material of the sleeve near the point of attachment 11 to the blouse body 12 has bunched only slightly as shown at 14, while the point X of the blouse has not moved upwardly beyond the waist belt 13. Comparing this with the similar action shown in the prior art structure of Fig. 2A substantial bunching is apparent about the shoulder and the point X has moved definitely above the waist line 13 as shown. Fig. 3 shows the blouse in accordance with the invention with the arm in the lowered position. Note that in this view the sleeve 10 returns to a substantially similar position to that shown in Fig. 1 with the upper portion of the sleeve being gently draped over the arm and presenting a well-groomed appearance. Contrary to this the prior art blouse of Fig. 3A shows a very definitely bunched sleeve and the blouse part has been pulled out from the waist belt 13 and no longer has the appearance observed in Fig. 1A. It is important to note in this connection that this improved sleeve operation has been attained through the utilization of a structure which provides added freedom and yet presenting an appearance very much similar to that presented by the conventional sleeve.

The structure of a sleeve at its point of attachment

11 to the blouse body 12 is illustrated in Figs. 4, 5 and 7, while Fig. 8 illustrates in part how this great freedom of action is attained. Referring now to Fig. 4 it will be observed that the sleeve 10 at its point of attachment to the blouse 12 has tapered edges 15 and 16 that are joined together to form a cylindrical sleeve. The tapered aspect of this sleeve from the shoulder line 11 is shown more clearly in Fig. 5. The edge 11 of the sleeve 10 has a contour which differs on each side of a vertical center line and includes reversely curved end sections. More 10 specifically and beginning at the edge 15, it will be noted that the contour of the edge 11 dips downwardly rather sharply to form a curved section 17 whereupon it curves upwardly to a maximum height 18 and then downwardly to a curved section 19 somewhat shallower than the curved section 17 to meet the opposing edge of the sleeve 16. The equivalent section of a prior art sleeve is shown in dotted outline on this figure to illustrate the substantial difference between the two contours. It will be observed that the width of the developed prior art sleeve is substantially narrower than the width of the sleeve in accordance with the invention and the slope of the top edge of the prior art sleeve is substantially steeper on each side of the center line than the sleeve in accordance with the invention. As will be shown the difference in these contours causes the sleeve to hang at different angles relative to the body of the blouse to which they are attached with the sleeve in accordance with the invention making a substantially larger angle with the body than the prior art sleeve. The contour of the edge 11 will perhaps be more clearly observed in Fig. 5 which shows the very definite depression 17 in the front section of the sleeve and a much shallower depression 19 in the rear portion thereof. This depression 17 serves to remove excess material from the front portion of the shoulder and avoids unnecessary blousing at this point which detracts from the garment's appearance. Fig. 7 shows the sleeve 10 in accordance with the invention in full cutline with the edge 11 aligned as closely as possible with the corresponding edge of the prior art sleeve shown in dotted outline. It will be observed that the peripheral lengths of both sleeve edges are substantially identical but the contour of the sleeve in accordance with the invention is materially different than the contour of the prior art sleeve.

The structure of this improved sleeve which provides a slightly larger sleeve diameter about the upper portion of the arm and also extends from the blouse at an angle of about twenty to thirty degrees below a horizontal line through the shoulder portions thereof provides considerably increased freedom and at the same time does not place any stress or strain on the blouse body itself as the arm is moved upwardly and downwardly. This feature is shown in Fig. 8 which has been arranged to emphasize this action. Since the sleeve of Fig. 8 rests at a relatively large angle with the body, it tends to drape downwardly over the arm from the shoulder of the blouse 12 to present the appearance as shown in Fig. 1 of the drawings. However, the arm 20 when in the lowered position as shown in full lines pulls the under edge 15, 16 of the sleeve downwardly against the body without bunching under the arm pit. However, as the arm starts to raise as shown at 20' a substantial portion of the movement is taken up within the sleeve itself and merely brings the sleeve to its normal position relative to the blouse 12. After the arm has passed this critical position and moves upwardly a further distance the material of the sleeve is free to move generally toward the shoulder

and permits the arm to be raised without pulling the blouse from beneath the waist 13. In the case of the prior art blouse shown in Fig. 9 a comparable movement of the arm starts to move the sleeve immediately in an upwardly direction and the narrowness of the sleeve together with its sharp angle causes the sleeve to catch about the upper muscle of the arm and prevent it from sliding downwardly toward the shoulder and ease the tension on the blouse body. In addition the slightly longer edges 15 and 16 which form the underseam of the sleeve in accordance with the invention provides sufficient added length at this point without undue accumulation of excess material to cooperate with the added sleeve diameter to relieve substantially the entire strain on the blouse as the arm is raised and lowered. In this way complete freedom of action is attained without disturbing the blouse and thus provides a blouse appearance that is not only superior after the blouse has been worn for an extended period of time but provides an improved appearance from the very beginning since the upper section of the sleeve is so arranged as to drape more naturally and uniformly about the arm.

While only one embodiment of the invention has been shown and described, it is apparent that modifications, 25 alterations and changes may be made without departing from the true scope and spirit thereof.

What is claimed is:

1. A garment comprising a body part having arm openings with the front and rear edges of said openings formed 30 as substantially smooth continuous curves extending in the generally vertical direction and a sleeve secured to each of said openings, each sleeve having front and back parts with the edges of said parts extending from a common upper point downwardly to a low point at an angle 35 of the order of magnitude of 20° to 30° with the axis of the sleeve, the edges of said parts further being in the form of S-curves with the front part being more deeply cut adjacent the lower end than the edge of the rear part and the peripheral edge of each sleeve having 40 substantially the same length as the edge of the cooperating arm opening whereby the sleeves and body may be joined without material puckering of the joined edges.

2. A garment comprising a body part having arm openings with the front and rear edges of said openings formed 45 as substantially smooth continuous curves extending in the generally vertical direction and a sleeve secured to each of said openings, each sleeve having front and back parts with the edges of said parts extending from a common upper point downwardly to a low point at an angle 50 of the order of magnitude of 20° to 30° with the axis of the sleeve, the edge of at least said front part being in the form of an S curve with the portion adjacent the lower end being more deeply cut than the corresponding portion of the rear part, and the peripheral edge of each 55 sleeve having substantially the same length as the edge of the corresponding arm opening whereby the sleeves and body may be joined without material puckering of the joined edges.
